UNITED STATES PATENT OFFICE

2,242,447

BRIDGE DUMMY SERVER

James D. Brown, San Antonio, Tex.

Application July 26, 1940, Serial No. 347,748

5 Claims. (Cl. 273—150)

This invention relates to a bridge dummy server.

An object of this invention is to provide novel means for bridge players to have a more efficient method for handling the dummy hand in bridge. It is customary to arrange the dummy hand in numerical order, providing the four suits in their respective order, and laying them face up in four rows, facing the bidder. In accordance with this invention, novel pockets are provided for receiving each of the dummy cards in such a way as to resemble the contour of the cards held by a hand; this factor will facilitate playing from the dummy as it will not become disarranged as so often happens with the old method; then, too, it permits the bidder to draw the dummy hand closer to the center of the table, thus avoiding reaching as far as in the old manner.

With the foregoing and other objects in view, the invention comprises certain novel constructions, combinations, and arrangement of parts as will be hereinafter fully described, illustrated in the accompanying drawing, and more particularly pointed out in the appended claims.

In the drawing:

Figure 1 is a plan view of a device constructed in accordance with the present invention, while

Figure 2 is a rear view of the same.

Figure 3 is a sectional view taken on lines 3—3, Figure 1, and looking in the direction of the arrows.

Figure 4 is an enlarged view of the left hand portion of the device, showing parts in section.

Figure 5 is a sectional view taken on line 5—5, Figure 4, and looking in the direction of the arrows.

Figure 6 is a sectional view taken on line 6—6, Figure 4, and looking in the direction of the arrows.

Figure 7 is a fragmentary view, partly in perspective and partly in section.

Referring to the drawing, in which I have shown the preferred embodiment of my invention, 1 designates a base unit, which comprises an elongated primary base element 2 and an auxiliary, elongated base element 3. These elements 2 and 3 are preferable made of suitable sheet-like material, or cardboard and are cut in the manner shown.

To the back of the base unit 1 are secured rest devices 4, whereby the base unit 1 is retained in a spaced position upon a support, as is clearly shown in Figure 3. Each rest device 4 is formed from suitable cardboard, and comprises an inner portion 5 (Fig. 3) an outer portion 6, a support

engaging portion 7 and an inner portion 8. Portions 5 and 8 are glued or otherwise fastened to the outer face of the primary base element 2 of the base unit 1.

Secured to the outer face of the auxiliary base element 3 are a plurality of pocket elements 9. Each pocket element 9 comprises an outer broad fold 10 and an inner short fold 11; these folds 10 and 11 are formed from one piece of material and the material is both strong and flexible, for allowing bending slightly, during the placing and the removal of the playing cards. The inner short fold 11 is glued, or otherwise fastened to the auxiliary base 3, and a straight spacer element 12 is fastened, preferably by gluing, under the outer fold 10 (Fig. 7); this spacer element constitutes the bottom of each spacer element 12 is securely glued to the inner short fold 11 and the outer broad fold 10, whereby the pocket element 9 is produced, for receiving a playing-card.

In the drawing, 13a designates the playing-cards.

By the novel structure described the pocket in each instant is left open, not only at the top, but also at the left hand side, whereby the playing cards 13a can be quickly and easily inserted or extracted from the pockets 13.

The auxiliary base element 3 not only strengthens the primary base element 1 but it gives a built-up structure, placing the pockets in a more raised position, for affording easy manipulation of the playing cards 13a.

While the preferred embodiment of this invention has been described and illustrated in the accompanying drawing, certain minor changes or alterations may appear to one skilled in the art to which this invention relates during the extensive manufacture of the same and, therefore, I reserve the right to make such changes or alterations as shall fairly fall within the scope of the appended claims.

What I claim is:

1. In a device of the class described, the combination of an elongated base unit, a plurality of flexible pocket elements extending transversely of said base unit, each pocket element provided with an inner short fold extending the height of the pocket element, a straight spacer element between each two contiguous pocket elements, said straight spacer element constituting the bottom of a pocket, each pocket element being open at its top, each pocket element being open at one side opposite to said short fold, and each pocket element fastened throughout its bottom to said straight spacer element.

2. In a device of the class described, the combination of an elongated base unit, a plurality of overlapping flexible pocket elements extending transversely of said base unit, said pocket elements being open along the upper longitudinal edge of said base unit, each pocket element including a straight spacer element at its bottom and a fold at one of its side edges, said straight spacer element attached partly to said fold and partly to a contiguous pocket element, and the fold attached directly to the base unit, and each pocket being open at its outer side edge opposite to said fold.

3. In a device of the class described, the combination of an elongated base unit, provided with a plurality of overlapping pocket elements, each pocket element provided with a rigid spacing element fastened partly to the pocket and partly to an adjoining pocket element, and each spacing element extending substantially lengthwise of the base unit and overlapping partly an adjoining spacing element.

4. In a device of the class described, the com-

bination of an elongated base unit provided with an upper edge, a series of pocket elements arranged in an arc of a circle upon said base unit, said pocket elements overlapping one another, each pocket element provided with stiffening reinforcing means at its bottom, said stiffening means of each pocket overlapping the stiffening means in an adjoining pocket element, and said pocket elements all opening upon the upper edge of said base unit.

5. In a device of the class described, the combination of a base unit provided with a plurality of overlapping pocket elements, each pocket element comprising an outer broad fold having an outer end and a free side edge, each pocket element provided with a rigid spacing element at its bottom overlapping a contiguous pocket element and its spacing element, and each rigid spacing element spacing the outer end and the free side edge of the outer broad fold of the pocket element from said base unit.

JAMES D. BROWN.
